United States Patent Office.

JOHN H. PARSONS, OF QUINCY, MICHIGAN.

Letters Patent No. 71,051, dated November 19, 1867.

LABEL-HOLDER FOR RAILROAD CARS.

The Schedule referred to in these Letters Patent and making part of the same.

TO ALL WHOM IT MAY CONCERN:

Be it known that I, JOHN H. PARSONS, of Quincy, in the county of Branch, and State of Michigan, have invented a new and useful Mode of Showing the Contents and Destination of Railroad Cars, in the form of a Label-Rack, which is fastened in plain view on the car; and I do hereby declare that the following is a full and exact description thereof, reference being had to the accompanying drawings, and to the letters of reference marked thereon.

The nature of my invention consists in providing a small iron or metal rack, with a lid hinged to the upper side of the rack. In the rack is placed a card or label, showing a full memorandum of the car, necessary to be seen by those having the car in charge while running from one point to another.

To enable others skilled in the art to make and use my invention, I will proceed to describe its construction and operation.

Figure 2 represents the label-rack as seen on the side of the car.

B is a rack, in which the label-card is held by means of flat springs, hereinafter more fully described. A is a lid or cover, hinged to the rack B at the top. In the lid is an opening, as shown at C, through which may be seen a part of the label, showing, without opening the lid, the destination of the car, as, for instance, Toledo to Chicago, showing that the car was consigned from Toledo to Chicago. Reference is made to Figure 3, which shows the detached label. But by opening the lid by the tip d, fig. 2, the whole of the label may be seen, upon which is written any desired memorandum in regard to the contents of the car, as dates, consignor and consignee of the goods, whether they be perishable or time goods; and, in case the car be delayed on the road, it may be noted on this label, the place and cause, thus keeping a memorandum with the car; and, in case the way-bills are lost, as is often the case, no damage may occur by a delay of the car, or any other reason, as a glance at the label shows at once a full memorandum, and agents or conductors may govern themselves accordingly. It is practised to some extent, by some roads, to tack a card on the car for the above purpose; but this card often gets destroyed or washed off by the rain; and to obviate this, and to furnish a permanent rack to hold the label, is the object of my invention.

To more fully explain its construction and operation, reference is made to fig. 1. I construct the rack B and lid A of malleable cast iron, brass, or other metal, of sufficient thickness, and of any desired size, in the shape and form as represented. The rack B is made with a cap or front projection, E, at the top, to protect the whole from rain. The corners y y are also made projecting in the form of a quarter circle, in connection with the cap E, to serve as ears, to which the lid A is hinged. The inside edges of the rack B are dished, or made like the easing of a door, shown at a a a a. The surface of the cross-slat k is made level with the edges a a a a; or the slat k may be made to fill the entire space inside the rack by making it wider. Two small thin strips of steel or spring brass are riveted to the lower side of the rack at p p, which place is also dished out enough that the top of the springs s s or surface is level with the surface of the rack B. These slips or springs are to hold the label in the rack, the upper ends of said springs s s being turned out a little in order that the label may be more readily slipped in behind them. In the lid C is the opening for the purpose heretofore stated. From the top, or a little above the opening, the surface of the lid is nearly flat or level, upon which may be made the letters standing for the road to which it belongs, as M. S. & N. I. (Michigan Southern & Northern Indiana.) The upper side of the lid is formed something in the shape of a half circle to cover the rod h. On the ends are made ears, similar to those at y y, into which they fit, (inside.) The inside of the lid, from the top to bottom, is on a level line, the curve spoken of being on the front side. The lid A is hinged to the rack B by the rod h, which passes through the ears on the lid and rack, and is headed over at the ends, one end being seen at e. In order to keep this lid closed, I form a coil-wire spring, m z, around the rod h, one end of which is fastened to the rack B, through the hole o, bending the end over on the back side. The other end is fastened to the lid A, through the hole w, bending the end over on the front side, as seen at w, fig. 2. By raising the lid it coils the spring m z, and thus the lid is always kept closed, protecting the label from being destroyed or lost. The rack B is fastened to the side of the car by the screws x x.

The labels may be made to suit the wants of different roads, in blank form, similar to the one shown in fig. 3. Therefore—

I claim as new, and desire to secure by Letters Patent—

The arrangement of the label-rack B, lid A, with the coil spring m z, substantially as and for the purpose described and set forth.

JOHN H. PARSONS.
